UNITED STATES PATENT OFFICE.

JERVIS R. HARBECK, OF DETROIT, MICHIGAN.

EXPLOSION-ENGINE.

1,174,494.

Specification of Letters Patent.

Patented Mar. 7, 1916.

Application filed February 25, 1911. Serial No. 610,912.

To all whom it may concern:

Be it known that I, JERVIS R. HARBECK, a citizen of the United States of America, residing at Detroit, in the county of Wayne 5 and State of Michigan, have invented certain new and useful Improvements in Explosion-Engines, of which the following is a specification, reference being had therein to the accompanying drawings.

10 The invention relates to explosion engines and has more particular application to engines of the two-cycle type.

15 It is the object of the invention to combine great flexibility with high efficiency and to this end the invention consists in the construction as hereinafter set forth.

20 In the drawings,—Figure 1 is a sectional plan view of the engine; Fig. 2 is a vertical cross-section through the engine on line $\alpha-\alpha$ of Fig. 1; Fig. 3 is a vertical longitudinal section on line $y-y$ of Fig. 1; Fig. 25 4 represents a detail.

25 My improvements are applicable to a single cylinder engine, but I have shown an engine of the multi-cylinder type in which A are the cylinders, B the crank case, C the piston, and D the pitman rod, of an engine of any suitable construction. The engine is of the two-cycle type and the air for forming the explosive mixture is transferred to the cylinder from the crank case as is common with engines of this type. The admission of air to the several compartments of the crank case is preferably controlled by 30 a rotary valve E arranged in the valve case F extending longitudinally at one side of the crank case.

35 G are transfer passages preferably arranged upon opposite sides of the cylinder 40 and conducting the air from the crank case, to ports H which are uncovered by the piston at the completion of its downward stroke. The exhaust port is arranged at the opposite end or head of the cylinder, 45 being preferably located in the lateral extension I, and as shown being controlled by a valve J of the puppet type. K is a cam shaft extending longitudinally of the engine casing having cams L thereon which 50 operate push rods M for actuating the respective valves J and the timing is such that said valves are opened in advance of the uncovering of the ports H by the piston. Thus 55 at the completion of each downward stroke of the piston the gaseous products of explosion will be exhausted by the opening of

the valve J and the cylinder will then be scavenged by a volume of air compressed in the crank case and transferred through the passages G and ports H, to the lower end 60 of the cylinder.

The air introduced into the cylinder to scavenge the same is also used for forming the new explosive mixture, but the fuel for carbureting the air is not introduced until 65 the exhaust valve is closed, thereby avoiding any waste. Furthermore, provision is made for varying the amount of the charge and with each variation maintaining the same ratio between the amount of hydrocarbon 70 fuel and air, the construction for accomplishing this result being as follows:

75 N is a rock shaft arranged parallel to the cam shaft K and connected by any suitable mechanism with a control lever.

O are eccentrics mounted on the shaft N which form fulcrum bearings for rock-arms P which extend between the cams L and their corresponding push rods M. The rock-arms P are fashioned to coöperate with the 80 cams L so that in all positions of adjustment of the shaft N and eccentrics O, the valves J will be opened at the same time with respect to the travel of their corresponding pistons, but the time of closing of said valves 85 varies with each adjustment of the rock shaft N. Thus, if the shaft N is adjusted to rock the eccentrics O away from the cam shaft K, the cam L will disengage from the portion Q of each arm P earlier in the stroke 90 of the piston and will close the valve J at such time. On the other hand, an adjustment of the shaft N in the opposite direction will delay the disengagement of the cams L from the portions Q and will main- 95 tain the valves J open for a longer period. By means of this mechanism the operator is enabled to control the volume of air which remains in the cylinder during the compression stroke of the piston. Where the closing 100 of the valve is delayed a portion of the volume of air originally introduced into the cylinder is expelled through the exhaust port and as the air thus expelled is that which was originally adjacent to the products of 105 combustion previously expelled, it is evident that the scavenging of any remaining burnt gases will be effected.

The fuel for carbureting the charge preferably liquid hydrocarbon, such as gasoline, 110 is introduced in the cylinder after the closing of the exhaust valve and as previously

stated the amount is proportioned to the volume of air in the cylinder upon the closing of said exhaust valve. As shown, the mechanism for introducing the oil consists of a 5 multiple pump having a plurality of separate cylinders and pistons corresponding to the number of engine cylinders. The cylinders R are preferably arranged in circular series in a case R', and each cylinder contains 10 a plunger or piston R² which extends upward out from the cylinder.

S is a rotary shaft arranged concentric with the series of cylinders and pistons being constantly driven from the engine, and 15 operating rotary cams T and W for actuating the plungers. The cam T is directly mounted on a sleeve T' which is longitudinally slidable but rotatively fixed to the shaft S, while the cam W is fixed directly to 20 the upper end of the shaft S.

S' is a collar on the shaft S which engages a vertically adjustable bearing S² operated by a worm S³ thereon and an engaging nut S⁴ which may be partially rotated by a lever 25 arm X. The arrangement is such that by a movement of the lever X and the connected parts operated thereby the shaft S is raised or lowered carrying with it the upper cam W, while the lower cam T remains fixed in 30 vertical position.

U is a shoulder providing a limiting stop for the upward movement of the plunger R² and also providing a seat for the spring U', which keeps the plunger forced against the 35 lower surface of the cam T until it is forced down by the rotation of the cam W. This adjustment is for the purpose of varying the stroke of the plungers R² which are operated in one direction by the cam T and in 40 the opposite direction by the cam W, the actuating portions of said cams being diametrically opposite each other. Thus by raising the shaft S the cam W is adjusted in 45 position so as to shorten the stroke of each plunger because the surface of the cam W in contact with the plunger R² is lessened, thereby lessening the quantity of oil that will be forced by the pump into the engine 50 cylinder. In other words, the operation is effected since the operating surfaces of the cams are diametrically opposite each other and therefore both cams are not in engagement with the same plunger at the same time, and consequently the cam T is not in 55 contact with the plunger when the cam W is forcing the plunger down.

It will be understood that with the apparatus just described each of the plungers R² will when operated, draw in and expel, a 60 measured quantity of oil which is conveyed through a conduit V to its corresponding cylinder. The amount of measured charge is varied correspondingly for all the pump pistons by an adjustment of the shaft S, this 65 being accomplished by a movement of the

lever X which is connected by a link X' with a rock arm X² on the shaft N. As the shaft N controls the time of closing of the exhaust valves for the engine, it is evident that any adjustment of said shaft changing the time 70 of closing will produce a corresponding adjustment of the shaft S at a corresponding variation in the quantity of oil conveyed to the cylinder.

With the construction described in operation, a full volume of air is admitted into the crank case upon each upward stroke of the piston and during the downward stroke thereof is compressed. As soon as the piston uncovers the port H this compressed air will be transferred to the cylinder where it will scavenge the products of combustion through the exhaust port previously opened by the operation of the valve J. The returning stroke of the piston will 85 continue to move the air in the same direction expelling a portion through the exhaust port until the valve J is closed, after which the remaining volume is compressed and during compression is mixed with the oil injected by the liquid pump. At the completion of the compression stroke the explosive charge is ignited and the cycle is repeated.

What I claim as my invention is:

1. In an explosion engine of the two-cycle type, the combination with a cylinder and piston therein, of means for exhausting the products of combustion and introducing a scavenging volume of air at opposite ends of said cylinder, means for varying the time of closing the exhaust passage to permit the expulsion of a portion of the scavenging air, and the compression of the remaining portion, and co-acting means for introducing a fuel charge after the closing of said exhaust valve and during the compression of the air in the cylinder.

2. In an explosion engine of the two-cycle type, the combination with a cylinder and piston therein, of a crank case in which air is compressed and transferred to the cylinder at the completion of the power stroke of the piston, a valve controlling an exhaust port at the opposite end of said cylinder from said transfer passage, means for opening said valve in advance of the transfer of said compressed air and for varying the time of closing of said valve whereby a variable volume is compressed in the cylinder, and co-acting means for introducing a fuel charge after the closing of said exhaust valve and during the compression of the air in the cylinder.

3. In an explosion engine of the two-cycle type the combination with a cylinder and a piston therein, of a crank case in which air is compressed and transferred to the cylinder at the completion of the power stroke of the piston, a valve controlling an exhaust port at the opposite end of said cylinder

from said transfer passage, means for opening said valve in advance of the transfer of said compressed air, and for varying the time of closing of said valve whereby a variable volume is compressed by the cylinder, means for introducing a fuel charge after the closing of the exhaust valve and during the compression of the air in the cylinder, and a connection between the fuel introducing means and the valve opening means for effecting upon an adjustment of the one a corresponding adjustment of the other.

4. In an explosion engine of the two-cycle type the combination with a cylinder and piston therein, of a crank case in which air is compressed and transferred to the cylinder at the completion of the power stroke of the piston, a valve controlling the exhaust port at the opposite end of said cylinder from said transfer passage, a cam shaft, a cam on said shaft, a second cam shaft, an

arm on said latter cam shaft coöperating with said cam to open the valve at a fixed point in the cycle, a pump for introducing liquid fuel into the cylinder, means timed to 25 actuate said pump to introduce the fuel after the valve has been closed, and means for adjusting the second cam shaft to variably close the valve, means controlling the operation of the pump to vary the quantity of 30 fuel introduced into the cylinder, and a connection between the last mentioned means and the means for adjusting the cam shaft whereby an adjustment of the one produces 35 a corresponding adjustment of the other.

In testimony whereof I affix my signature in presence of two witnesses.

JERVIS R. HARBECK.
